SASHLESS WINDOW STRUCTURE

Remuald Migneault and Fernand W. Migneault, both of
332 St. Andre St., Gatineau, Quebec, Canada
Filed Mar. 30, 1960, Ser. No. 18,526
3 Claims. (Cl. 26—52)

This invention relates to sashless window structures. Sashless windows are now in widespread production and use because of their simple and inexpensive structure and because of their convenient, effective and satisfactory operation. However, it has heretofore been considered that, in order to gain the full advantages of such structures, it is necessary to employ the glass panels thereof in horizontal sliding position. Thus, such a structure results in a radical departure, as compared with conventional double hung windows, in respect of the size and shape of the window opening. As a result, such window openings are usually of rectangular shape, which in itself is a standard condition, but with the major dimension thereof disposed horizontally rather than vertically as is the case in most double hung window installations. This condition imposes a major restriction in the window openings available for reception of sashless windows.

It is an object of this invention to provide a sashless window structure wherein the glass panels thereof are disposed for vertical sliding movement.

A more specific object is to provide a sashless window structure having simple mounting means for the glass panels thereof whereby such panels may be readily and satisfactorily disposed for vertical sliding movement.

Other objects, details and advantages of the invention will be apparent from the following description with particular reference to the accompanying drawing, in which:

FIGURE 1 is a front elevation of a window structure in accordance with the invention,

FIGURE 2 is a partial sectional perspective view of the window structure,

FIGURE 3 is a sectional view on line 3—3 of FIGURE 1, and

FIGURE 4 is an enlarged sectional elevation of panel locking means.

In the drawing, 1 is a frame which may be formed of wood and which has a sill 2, head piece 3, and jambs 4 and 5.

Mounted on the inside face of each jamb 4 and 5 and extending substantially from the sill to the headpiece is a track member 6 which may be formed of any suitable metal or plastic composition and which is preferably of unitary form. Each track member 6 comprises a base strip 7 which is anchored to the jamb by a suitable means such as a pair of ribs 8 extending into grooves 9 in the jamb and having flanged edges 10 fitting into recesses 11 in the walls of the grooves. The upper portion of each base strip 7 is provided with a panel retaining flange 12 extending along the rear edge thereof. The lower portion of each base strip 7 is also provided with a panel retaining flange 13 which may be a continuation of flange 12 but which is provided with an inner panel engaging strip 13a which terminates in a shoulder 14 adjacent the midsection of the frame. The lower portion of each base strip 7 is also provided with a panel retaining flange 15 extending along the front edge thereof and terminating adjacent the midsection of the frame. Flange 15 is also provided with an inner panel engaging strip 15a which terminates with the flange. The front edge of the upper portion of each base strip is free of obstruction as indicated at 16. It will thus be apparent that the track members 6 are of channel formation in the lower portions thereof. The inner surface of each base strip 7 is disposed in a normally vertical plane located

2

inwardly of the plane of the adjacent forward surface 17 of the frame.

A top panel 18 of plate or like glass is arranged to be seated with its lower edge resting on shoulders 14. In 5 this position, the upper edge of panel 18 is adapted to be received in a groove 19 in the head piece, the side edges thereof in approximate engagement with the inner surfaces of base strips 7, and rear face portions in engagement with retaining flanges 12. It will be apparent that 10 by exerting a tilting movement on the panel, it may be readily disposed in or removed from such position.

A bottom panel 20 of plate or like glass is arranged to be slidably mounted in the lower channel portion of 15 the base strips 7 with its upper edge portion 21 overlapping and engaging panel 18, its side edges in approximate engagement with the inner surfaces of base strips 7, and its rear face portions in engagement with retaining flanges 13.

Means are provided for imparting vertical sliding 20 movement to panel 20 and comprises, as shown, a channel 22 of metal, plastic composition or the like embracing the lower edge portion of the panel and secured thereto as by a layer of adhesive 23. The channel has a forwardly projecting horizontally disposed flange 24 which 25 may be grasped to impart manually sliding movement to the panel.

Means are provided for locking panel 20 in one of a series of selected open positions. Such means may comprise a pair of panel locks 25 each having a locking bar 26 reciprocally mounted in a recess 27 in channel 22. The end of bar 26 is urged outwardly of recess 27 by means of a spring 28 engaging the bar and having one end seated on a lug 29 in the recess. The bar 26 is slidable against the action of the spring by means of a handle 30 fixed to the bar by means of a pin 31 which extends through a slot 32 in the flange 24. Each flange 15 has a rectangular notch 33 adjacent the lower end thereof for reception of the end of bar 26 to define the closed and locked position of panel 20. Each flange 15 35 also has a plurality of spaced notches 34 for reception of the end of bar 26 and defined by a flat horizontally disposed bar-engageable edge 35 and a curved edge 36 engageable by a curved end surface 37 of the bar. It will be apparent that each notch 33 and 34 on one flange 15 is in lateral alignment with a notch 33 and 34 on the other flange 15. It will also be apparent that, with the bars 26 disposed in notches 33 to lock the panel in closed position, manual withdrawal of the bars will permit raising of the panel and that the bars will automatically move 40 into the pairs of aligned notches 34 to position the panel in any one of a series of panel opening positions of varying degree.

Means are provided for resiliently urging panel 20 into close fitting engagement with strips 13a as well as urging 45 the overlapping portion of panel 20 into engagement with panel 18. Such means may comprise a pair of housings 35a, each mounted on a jamb 4 or 5 and carrying a bracket 36a having a panel-engaging roller 37a, the bracket and roller being urged towards the panel by a spring 38.

Means for separating the panels 18 and 20 during 50 opening movement of panel 20 to facilitate such movement may comprise a pair of protuberances 39 fixed to panel 18 immediately above the edge of panel 20 in the closed position thereof.

The window structure may be provided with any suitable weatherstripping means. As shown, this means may comprise a collapsible rubber or like resilient strip 40 anchored in the lower edge of channel 22 and engageable 55 with the sill 2 in the closed position of panel 20. Further, strip 13a may be of resilient character, such as rubber, to constitute a weatherstripping means.

It will be apparent that both panels 18 and 20 are readily removable from the tracks and frame for cleaning, replacement, and easy installation purposes. Thus, panel 20 may be slid upwardly until the lower edge thereof clears the upper ends of strips 15 and 15a, when the panel may be moved forwardly out of the tracks and frame. Thereafter, the panel 18 may be also moved forwardly out of the tracks and frame. Re-installation of the panels is accomplished in a like simple manner.

We claim:

1. A sashless window comprising a frame having a sill, a head piece, and jambs, a pair of unitary plastic composition tracks separable from said frame and each having means anchoring it to one of said jambs, each said track comprising a base strip having plane inner and outer parallel side surfaces and longitudinal edge surfaces, said outer side surface being in abutment with one of said jambs, a first flange extending perpendicularly from said inner side surface adjoining one of said edge surfaces and from end to end of said strip, said flange having one portion of increased thickness extending from said sill, a shoulder terminating said one portion and extending perpendicularly from said inner surface, and a second portion of reduced thickness extending from said shoulder to said head piece, and a second flange parallel to said first flange and disposed perpendicularly to said inner surface and extending from said sill to a point in opposed relation to a point on said one portion of said first flange, a top sashless glass panel having a lower edge seatable on said shoulders and an upper edge engageable with said head piece, a bottom sashless glass panel arranged for slidable mounting between said flanges and having a lower edge seatable on said sill, said panels having overlapping glass-to-glass contact, and pressure applying means mounted on one of said jambs and engaging said bottom sashless panel in the overlapping area thereof, the entire portion of said inner surface of said base strip lying opposite said flange portion of reduced thickness being unobstructed to permit forward withdrawal therefrom of said panels.

2. A sashless window as defined in claim 1, said anchoring means comprising a pair of spaced parallel ribs on said outer side surface and extending longitudinally thereof and each having flanged edges, said jamb having grooves therein for reception of said ribs.

3. A sashless window as defined in claim 1, including means for imparting sliding movement to said bottom panel comprising a channel fixed to the lower edge of said bottom panel, and a flange on said channel in parallel relation to said lower edge, and means for locking said bottom panel comprising a pair of spring-urged locking bars carried by said channel flange, and a locking strip fixed to each said jamb and extending perpendicularly from said sill, each said locking strip having a plurality of longitudinally spaced notches therein for reception of said locking bars, the lowermost of said notches in each said locking strip adjacent said sill having a pair of opposed parallel shoulders for locking engagement by said locking bar, each of the others of said notches having a shoulder perpendicular to said jambs and engageable by said locking bar to restrain said bottom panel from downward movement and a surface extending angularly upwardly from said last-mentioned shoulder and engageable by said locking bar to withdraw said locking bar and permit upward movement of said bottom panel.
